Primary Examiner — Katherine A Holbrow(74) *Attorney, Agent, or Firm* — Studebaker & Brackett PC(57) **CLAIM**

The ornamental design for a display screen with animated graphical user interface, as shown and described.

DESCRIPTION

FIG. 1 is a front view of a display screen with animated graphical user interface, showing a first embodiment of our new design;

FIG. 2 is an enlarged view of graphical user interface of a first image in a sequence;

FIG. 3 is an enlarged view of graphical user interface of a second image thereof; and,

FIG. 4 is an enlarged view of graphical user interface of a third image thereof.

The appearance of the animated graphical user interface sequentially transitions between the images shown in FIGS. 2-4. The process or period in which one image transitions to another image forms no part of the claimed design. The outer peripheral broken lines represent a display screen or portion thereof and form no part of the claimed design. The dash-dot broken lines define the bounds of the claimed design and form no part thereof.

1 Claim, 4 Drawing Sheets(56)
